UNITED STATES PATENT OFFICE.

WILLIAM E. BENN AND GEORGE E. DAVIES, OF TROY, NEW YORK, ASSIGNEES TO THE UNITED STATES TRAIN SIGNAL COMPANY, OF PORTLAND, MAINE, A CORPORATION OF MAINE.

CONTROLLER FOR TRAIN-SIGNAL SYSTEMS.

Application filed May 10, 1920, Serial No. 380,287. Renewed June 5, 1924.

To all whom it may concern:

Be it known that we, WILLIAM E. BENN and GEORGE E. DAVIES, citizens of the Dominion of Canada, residing at Troy, in the county of Rensselaer and State of New York, have invented certain new and useful Improvements in Controllers for Train-Signal Systems, of which the following is a specification.

10 Our said invention relates to controllers for use in train signal systems and it consists in the details of construction and arrangement of parts whereby such a device is provided which is very convenient for 15 use and reliable in its operation, all as will be hereinafter more fully described and claimed.

20 Referring to the accompanying drawings which are made a part hereof, and on which similar reference characters indicate similar parts,

25 Figure 1 is a view showing the frame or casing of the controller in section and the mechanism thereof in elevation,

Figure 2 is a similar view in plan,

Figure 3 a detailed view of the contact block forming a leading feature of said device, and

30 Figure 4 a diagrammatic view showing a modified arrangement.

In said drawings, the portions marked A represent the casing and B the frame.

Within the frame B is mounted a sliding rod 10, said rod adapted to slide in apertures in the ends of the frame. A block 11 is rigidly secured midway of said rod 10 preferably formed of insulating material with a metallic contact plate 12 mounted on one face thereof. Springs 13 are interposed 35 between said block and the ends of the frame and are adapted to normally hold said block positioned centrally within said casing.

40 Spring contact arms 14 are mounted on binding posts 15 and are connected with wires 16 which form opposite sides of an electric circuit, said circuit being the circuit designed for controlling the signals throughout the train.

45 The particular type of signaling system for which this controller is especially designed forms the subject matter of another application No. 380,286, filed by us of even date herewith and further illustration of

this particular device is therefore thought unnecessary.

In operation, the ends of the rod 10 being connected by a signal cord, or otherwise, throughout the train, a member of the train crew may operate the same by pulling on said cord, which operates to slide the rod 14 one way or the other and disconnect one arm 14 or the other from its contact with the contact plate 12 and thus breaks the circuit. As soon as the circuit is broken, the "danger" signal is operated. On releasing the operating cord, the springs 13 operate to return the parts to normal position, bringing both arms 14 in contact with the plate 12 and closing the circuit and restoring the signals to "safety" position. It will be understood, of course, that in any arrangement wherein it is desired to have the circuit normally open the operation of the controller would be the reverse of that just described. The same principle will also apply in a multiple switch.

Having thus fully described our said invention, what we claim as new and desire to secure by Letters Patent, is:

1. A controller for train signaling systems, comprising a frame, a sliding bar mounted therein, means connected to each end of the bar whereby it may be moved, a contact plate mounted midway of said bar and insulated therefrom, springs for normally holding said contact plate midway of said frame, and terminal contact arms adapted to make contact with said plate, thus completing an electric circuit, substantially as set forth.

2. A controller for opening and closing the circuit of an electrically operated signal system comprising a reciprocating bar, a contact plate carried thereby and insulated therefrom and normally in contact with the terminals of the circuit, means for normally holding said plate in position for closing the circuit and means for manually sliding said bar in either direction to break the circuit, as substantially set forth.

3. A controller for the circuit of an electrically operated signaling system comprising a sliding contact plate arranged to contact with the terminals of the two sides of the circuit in one position and to be out of contact with one while retaining contact

- with the other in another position and means to automatically return to and retain said contact plate in normal position when the operating force is removed.
5. 4. In combination, a pair of contact arms, a plate adapted to contact therewith, resilient means acting on said plate to hold the same in central circuit closing position and oppositely acting means whereby the 10 plate may be moved to either side of the central position to break the circuit, substantially as set forth.
5. In a circuit breaker, a pair of spaced contacts, circuit closing means normally 15 contacting with both contacts, means to move the same selectively out of engagement with either contact, and means for returning the circuit closing means to normal position, substantially as set forth.
- 20 6. A circuit controller comprising a pair of spring contact arms, a plate adapted to contact therewith to close the circuit, a bar supporting the plate and having rectilinear

movement, springs surrounding said bar at each side of the plate and cords attached to 25 the ends of the bar by which it may be moved against the action of the springs, substantially as set forth.

7. In combination, a support, a bar slidably mounted thereon, a single contact plate 30 on the bar, oppositely located terminals adapted to contact therewith to close the circuit, resilient means acting on the bar to maintain the contact plate in central position on the support, and means whereby said 35 plate may be drawn toward either end of the support, substantially as set forth.

In witness whereof, we have hereunto set our hands and seals at Washington, District of Columbia, this fifth day of April, 40 A. D. nineteen hundred and twenty:

WILLIAM E. BENN [L. S.]
GEORGE E. DAVIES [L. S.]
